UNITED STATES PATENT OFFICE.

EARL E. EICKMEYER, OF DAYTON, OHIO, ASSIGNOR TO THE NATIONAL RECORDING PUMP COMPANY, OF DAYTON, OHIO, A CORPORATION OF OHIO.

LOCK FOR FLUID-DISPENSING APPARATUS.

Application filed February 5, 1925. Serial No. 6,976.

To all whom it may concern:

Be it known that I, EARL E. EICKMEYER, a citizen of the United States, residing at Dayton, in the county of Montgomery and

5 State of Ohio, have invented certain new and useful Improvements in Locks for Fluid-Dispensing Apparatus, of which the following is a specification, reference being had therein to the accompanying drawing.

10 This invention relates to a lock for fluid dispensing apparatus and is designed more particularly for use in connection with oil dispensing apparatuses, such as are commonly used at automobile filling stations.

15 Oil dispensing apparatuses of this character are frequently left unprotected during the absence of the attendant and not infrequently are left out of doors over night. It is therefore desirable that some 20 means should be provided to prevent the operation of the pump and for preventing access to the interior of the tank during the absence of the attendant, and one object of the present invention is to provide such 25 means and, further, to so arrange the same that both the operation of the pump and the closure for the tank will be controlled by a single lock.

Dispensing apparatuses of this character 30 are usually located in more or less exposed positions where persons other than the attendant are present or passing and it not infrequently happens that some such person will inadvertently or otherwise impart 35 movement to the pump handle thus causing a loss of oil. To avoid such unauthorized operation of the pump it is a further object of the invention to provide a latch or temporary lock which is manually controlled 40 and which may be positioned normally to prevent the operation of the pump handle.

These dispensing apparatuses are also sometimes provided with drip pans to catch any drippings from the delivery spout or oil 45 which may be spilled from the measure into which it is discharged from the spout. Where such a pan is loosely mounted on the apparatus it is not infrequently lost, either accidentally or due to its removal by 50 boys or other unauthorized persons. A further object of the present invention is to provide means, controlled by the lock for the other parts of the mechanism, which will

also prevent the removal of this pan by unauthorized persons.

Other objects of the invention will appear as the apparatus is described in detail.

In the accompanying drawings Fig. 1 is a side elevation of a dispensing apparatus, showing only the top wall of the tank; Fig. 2 is a section taken on the line 2—2 of Fig. 1, and partly broken away; Fig. 3 is a detail view of the locking device for the pump showing the same in its operative position; Fig. 4 is a similar view showing the locking device in its inoperative position; and Fig. 5 is a detail view of the lock for the closure for the filling opening to the tank.

In these drawings I have illustrated one embodiment of my invention and have shown the same as applied to an oil dispensing apparatus of a known character but it will be understood that this particular embodiment has been chosen for the purpose of illustration only and that the locking devices may take various forms and may be applied to dispensing apparatus of various kinds without departing from the spirit of the invention.

In that apparatus here illustrated the top wall of the tank is shown at 1 and mounted on this top wall is a base, preferably in the form of a casting 2, on which the dispensing apparatus is mounted. Rising from this base is a hollow standard 3 on the upper end of which is supported a cylinder 4 which, in the present instance, is of glass and which communicates with the tank through the hollow standard. The upper head of the cylinder 4 is provided with a discharge spout 6. Mounted in the cylinder is a piston 7 having a piston rod 8 in the form of a toothed rack bar which extends downwardly into the standard 3 and meshes with a pinion 9 mounted on a shaft 10 journaled in the walls of the standard and which is provided on its outer end with an operating handle or crank 11 by means of which the pinion may be rotated to impart reciprocating movement to the piston. The base 2 is provided with a filling opening which is in line with a corresponding opening in the top wall 1 of the tank and which is provided with a swinging closure or cap 12. This cap is here shown as having a laterally extending arm 13 by means of which it is

5 pivoted at 14 on the base 2. Projecting from one edge of the closure is a stop finger 15 arranged to engage a stop lug 16 on the base 2 when the closure is in its closed position and the stop finger and the lug are provided with registering openings to receive a locking device, such as the hasp of a padlock 17, to secure the closure or cap in its closed position.

10 The holding or locking device for the handle 11 of the pump may take various forms but, in the present instance, the handle is so arranged that it will be in its lowermost position, as shown in Fig. 1, when the piston 15 is in its lowermost position, and the holding or locking device, which is shown at 18, is pivotally mounted at 19 on a bracket 20 carried by the base 2. This locking member comprises a finger 21 which is movable into and out of operative relation with the handle 11. In the present construction the handle is provided at its outer end with a recess 22 into which the locking finger 21 may be moved. The locking finger is retained in 25 its operative or its inoperative position by means of a rod 23 which is slidably supported at one end in the bracket 20 and at its other end in the lug 16, the guide opening in the lug 16 being counterbored to receive the head 24 of the rod. Thus the head of the rod will limit its movement in one direction and the rod will be held against movement in the other direction by the stop finger 15 of the closure 12 when this closure is in its 30 closed position. The end of the rod projects beyond the bracket 20 and into the path of the locking finger 21. When this locking finger is in its locking position, as shown in Fig. 3, the rod will lie beneath the same and will positively prevent its withdrawal. When the locking finger is in its 35 inoperative position, as shown in Fig. 4, the rod will lie above the finger and will prevent its moving into an operative position but will allow it a limited amount of swinging movement, the purpose of which will hereinafter appear. In this manner the lock 17 serves to positively control the movements both of the closure 12 and of the pump 40 operating handle 11.

45 Associated with the locking member 18 and preferably forming an integral part thereof is a latch 25, which is here shown in the form of a finger movable into and out of operative relation to the handle 11, this handle being in the present instance, provided with a lug 26 to cooperate with the latch 25. The locking member is also provided with a finger piece 27 by means of which the latch may be moved into and out of its operative position. The locking member as a whole, including the locking finger 21, the latch 25 and finger piece 27, is so balanced that when the latch 25 is moved 50 into its operative position or into its inop-

erative position the center of gravity of the locking member as a whole will be shifted from one side of its axis to the other, thus causing the latch to be retained by gravity in either position to which it may be moved. 70

75 Mounted on the closure 12 is a housing 28 the upper wall 29 of which constitutes a support for the measuring cup or other receptacle into which the oil is discharged from the spout 6, this wall having its central portion depressed so that it will slope toward a central opening, thereby causing any oil which may be deposited thereon to drain through this central opening into a drip pan 30 which is supported within the housing 80 beneath the opening. The housing 28 is provided with an opening 31 through which the drip pan may be inserted and removed and this opening is so arranged with relation to the closure 12 that when that closure 85 is in its closed position the opening will lie adjacent to the standard 3 and will be positioned so close thereto that the pan 30 cannot be removed. Consequently the lock 17 which retains the closure in its closed 90 position will also prevent the removal of the drip pan 30.

95 While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

100 1. The combination with a tank having an opening, a closure for said opening, and a pump mounted on said tank and having an operating handle, of means comprising a single lock for holding said closure and said handle against movement.

105 2. The combination with a tank having an opening, a closure for said opening, and a pump mounted on said tank and having an operating handle, of a locking device for said closure and said handle comprising a lock for one of said members, and means controlled by said lock for holding the other of said members against movement.

110 3. The combination with a tank having an opening, a closure for said opening, and a pump mounted on said tank and having an operating handle, of a lock to secure said closure in its closed position, and means controlled by said lock to hold said handle against operative movement.

115 4. The combination with a tank having an opening, a closure for said opening, and a pump mounted on said tank and having an operating handle, of a lock to secure said closure in its closed position, a device to hold said handle against operative movement, and means controlled by said lock to retain said device in its operative position.

120 5. The combination with a tank having an

opening, a closure for said opening, and a pump mounted on said tank and having an operating handle, of a device for holding said handle against operative movement, 5 said device comprising a longitudinally movable rod, a lock for said closure, and means controlled by said lock to hold said rod against longitudinal movement.

6. The combination with a tank having 10 an opening, a closure for said opening, and a pump mounted on said tank and having an operating handle, of a device for holding said handle against operative movement, said device comprising a longitudinally movable rod, a locking member carried by 15 said closure, a fixed locking member to cooperate with the first mentioned locking member, said first mentioned locking member being so arranged that when in operative relation to said fixed locking member it 20 will hold said rod against longitudinal movement, and means to hold said locking members against relative movement.

7. The combination with a tank having 25 an opening, a closure for said opening, and a pump mounted on said tank and having an operating handle, of a lock to secure said closure in its closed position, a pivoted locking member movable into and out of operative relation to said handle, and a device 30 controlled by the lock for said closure for securing said pivoted locking member in its locking position.

8. The combination with a tank having an 35 opening, a closure for said opening, and a pump mounted on said tank and having an operating handle, of a lock to secure said closure in its closed position, a locking member movable into and out of operative relation 40 to said handle, a longitudinally movable rod movable into and out of a position to control the movement of said locking member, and means controlled by the lock for said closure to hold said rod against longitudinal movement.

9. The combination with a tank having an opening, a closure for said opening, and a pump mounted on said tank and having an operating handle, of a locking member movable 50 into and out of operative relation with said handle, a stop carried by said closure, a fixed stop cooperating with the first mentioned stop, a rod slidably mounted in said fixed stop and having one end movable into 55 a position to control the movement of said locking member, said rod having a head to hold it against movement in one direction and being held against movement in the other direction by the stop on said closure 60 when the latter is in its closed position, and means for securing said closure in its closed position.

10. The combination with a pump having 65 an operating handle, of a locking device having a part movable into and out of lock-

ing position with relation to said handle, and means for securing said part in said operative position, said locking device also having a part which is movable into and out of locking position with relation to said handle while the first mentioned part is out of locking position. 70

11. The combination with a pump having an operating handle, of a locking device having a part movable into and out of locking position with relation to said handle and means for securing said part in said operative position, said locking device also having a part which is movable into and out of locking position with relation to said handle while the first mentioned part is out of locking position, said locking device being so balanced that the last mentioned part will be held in either its operative or inoperative position by gravity. 75

12. The combination with a pump having an operating handle, of a pivoted locking member having a finger movable into and out of operative relation to said handle, and means for securing said locking member with said finger in its operative position, said locking member also having a second finger which is movable into and out of operative relation to said handle while the first mentioned finger is in its inoperative 95 position.

13. The combination with a pump having an operating handle, of a pivoted locking member having a finger movable into and out of operative relation to said handle, and means for securing said locking member with said finger in its operative position, said locking member also having a second finger which is movable into and out of operative relation to said handle while the first mentioned finger is in its inoperative position, said locking member being so balanced that its center of gravity will be movable across its axis by the movement of said second locking finger into its operative or inoperative position. 100

14. The combination with a tank having an opening, a closure for said opening, and a pump mounted on said tank and having an operating handle, of a pivoted locking member having a part movable into and out of operative relation to said handle and having a second part which is movable into and out of operative relation to said handle while the first mentioned part is in its operative position, a rod having longitudinal movement to control the position of the first mentioned part of said locking member, and means for locking said closure in its closed position and for retaining said rod against longitudinal movement. 115

15. The combination with a tank having an opening, a closure for said opening, a pump mounted on said tank and having an operating handle, and a drip pan removably 120

- mounted on said closure, of a single lock for securing said handle against movement, retaining said closure in its closed position and preventing the removal of said pan.
- 5 16. The combination with a tank having an opening, a closure for said opening, and a pump mounted on said tank and having an operating handle, of a housing carried by said closure and having an opening through 10 which a drip pan may be inserted in or re-

moved from said closure, said opening being so arranged that it will lie adjacent to said pump when said closure is in its closed position, a device for locking said handle against operative movement, and a lock for 15 securing said closure in its closed position and for controlling said locking device.

In testimony whereof, I affix my signature hereto.

EARL E. EICKMEYER.
